UNITED STATES PATENT OFFICE.

SAMUEL S. ST. HOOR, OF KANSAS CITY, MISSOURI.

DESIGN FOR A COMBINED HEATING AND ILLUMINATING DEVICE.

No. 38,350.

Specification for Design.

Patented Dec. 11, 1906.

Application filed October 26, 1906. Serial No. 340,776. Term of patent 14 years.

To all whom it may concern:

Be it known that I, SAMUEL S. ST. HOOR, a citizen of the United States, residing at Kansas City, in the county of Jackson and State of Missouri, have invented a new, original, and ornamental Design for a Combined Heating and Illuminating Device, of which the following is a specification, reference being had to the accompanying drawing, forming part thereof.

The figure is a perspective view of a combined heating and illuminating device, showing my new design.

I claim—

The ornamental design for a combined heating and illuminating device, as shown.

SAMUEL S. ST. HOOR.
